UNITED STATES PATENT OFFICE.

GEORGE LINCOLN ESTES, OF OKLAHOMA CITY, OKLAHOMA, ASSIGNOR OF ONE-HALF
TO O. C. STRODE, OF OKLAHOMA CITY, OKLAHOMA.

DESIGN FOR A TRAFFIC SIGNAL.

Application filed September 5, 1924. Serial No. 10,688. Term of patent 14 years.

To all whom it may concern:

Be it known that I, GEORGE LINCOLN ESTES, a citizen of the United States, residing at the Imperial Hotel, 310½ North Broadway, in Oklahoma City, in the county of Oklahoma, State of Oklahoma, have invented a new, original, and ornamental Design, the title of which is a Traffic Signal, of which the following is a specification,

reference being had to the accompanying drawing, forming part thereof.

Figure 1 is a face view, and

Figure 2 a view at right angles to Figure 1.

I claim:

The ornamental design for a traffic signal, as shown.

GEORGE LINCOLN ESTES.
